UNITED STATES PATENT OFFICE.

ELLSWORTH GRIFFIN, OF MILWAUKEE, WISCONSIN.

PERFORATING-MACHINE.

SPECIFICATION forming part of Letters Patent No. 556,714, dated March 17, 1896.

Application filed March 5, 1895. Serial No. 540,639. (No model.)

To all whom it may concern:

Be it known that I, ELLSWORTH GRIFFIN, a citizen of the United States, and a resident of Milwaukee, in the county of Milwaukee and State of Wisconsin, have invented certain new and useful Improvements in Perforating-Machines; and I do hereby declare that the following is a full, clear, and exact description thereof.

10 My invention has for its object to provide a simple, economical and efficient perforating-machine by which money values of bank-checks or analogous orders may be expressed in words instead of numerals, thus rendering it more difficult to raise such orders; and said invention consists in certain peculiarities of construction and combination of parts hereinafter described with reference to the accompanying drawings and subsequently claimed.

15 In the drawings, Figure 1 represents a plan view of my machine, partly in horizontal section and partly broken away; Figs. 2 and 3, sections of the same respectively taken on lines 2 2 and 3 3 of the preceding figure; Fig. 25 4, a plan view of the index-plate at the top of the machine; Figs. 5 and 6, detail plan views, partly in horizontal section; and Fig. 7, an elevation of a pawl-and-ratchet mechanism that constitutes a detail of the machine.

30 Referring by letter to the drawings, A represents the base of my machine in the form of a hollow circular casting having an angular front extension B, and surmounting this base is a circular housing C, held in place by

35 screws b or other suitable means.

The machine-base is herein shown as provided with a depending central boss c, and adjustable in this boss is a conical pointed screw d that constitutes one of the bearings 40 for an arbor D, a set-nut e being employed to maintain the screw in adjusted position. The other bearing, d', for the arbor is central of the housing C, and this housing is provided at its lower end with an interior annular 45 flange f, that serves as a track for another annular flange g on the outside of a shell E, that has a central hub h made fast to the arbor D by a set-screw i or other suitable means.

50 Rigidly secured to the lower edge of the shell E by screws j or other suitable means is an inwardly-extended circular plate F, and

riveted or otherwise fastened tight to the inner edge of this plate is another plate G, these plates being spaced apart by a washer k between their inner ends, as clearly illustrated in Figs. 2 and 3.

Within the shell E, above the plate F, is a horizontal flange H, provided at intervals with vertical openings that are loosely engaged by stems I of variable length, and surrounding each stem intermediate of its head m and said flange is a spiral spring J of suitable power. On the lower end of each stem is a block K, that opposes the under side of the shell-flange H, and one function of the block is that of a stop to limit upward movement of said stem.

The blocks K are of different lengths, and depending from each of these blocks are a series of pins arranged to form the outlines of an arbitrary symbol or the letters of an arbitrarily-selected syllable or word, and these pins are in line with corresponding openings in the parallel plates F G above specified. The openings in the upper plate, F, are always engaged by the pins depending from the blocks K and serve as guides for the same, the lower ends of said pins being flush with the under side of said plate or retracted therein when the stems I are in their normal position. The spring-controlled stems, the blocks at their lower ends and the pins depending from the blocks constitute what are hereinafter designated as "dies."

At the front of the machine the housing is provided with an opening that registers with the space intermediate of the perforated plates F G, and crossing said space against the washer k between said plates is a gage-strip L that is made fast at its ends to said housing by screws or other suitable means.

The dies are indexed on a plate M that is fast on the arbor D above the housing C, and opposite each index is a vertical knob n in register with a peripheral notch, the notches being engageable with the free end of a spring-stop p attached to said housing, as shown in Fig. 2.

Pivotedly connected to a standard N on the machine-base, within the shell E, is the central portion of a shank P pertaining to a hammer Q, and this hammer is brought against the dies above specified by a mech-

anism hereinafter described. As herein shown the hammer-shank is forked to straddle its supporting-standard and the arbor D, and a spiral spring R depends from a rod 5 connecting the fork branches. The lower end of this spiral spring is joined to a bracket S that depends from the top of the machine-base, and said spring acts to automatically return the hammer to normal position after an operation necessary to force down one of the perforating-dies.

A link T joined to the hammer-shank adjacent to the head connects with a spring-resistant lever U, the latter being pivoted at its 15 inner end to the wall of the machine-base, inside of the same. The lever extends across the front extension of the machine-base to play in a slot in the wall of this base, and the outer or handle portion V of said lever 20 comes within easy reach of the right hand of the operator, his left hand being employed to manipulate the index-plate M, thus causing any desired die to the perforating-point under the head of the hammer.

An opening r in the lever U is engaged by a projection s on a counterweighted arm W, that is loose on the axle t of a feed-roller X, this axle being supported in suitable bearings 30 on the machine-base, within the same, and pivotally connected to the arm is a pawl Y, that engages with a ratchet-wheel Z fast on said axle. The pawl is held against the ratchet-wheel by means of a spring u, and the counterweight w of the pawl-arm W prevents the latter from dropping down farther than necessary when an action of the lever U takes place.

A spring-controlled detent x is pivotally 40 hung from the top of the machine-base to engage the ratchet-wheel Z and thereby prevent reverse movement of the feed-roller X above specified.

The feed-roller X extends up through an 45 opening in the top of the machine-base, and another feed-roller, X', parallel to the first, is journaled in a spring-controlled frame A' in hinge connection with the outside of the housing C, this frame being provided with a handle y, by which it may be swung upward 50 against the resistance of the opposing spring or springs z, the latter being clearly illustrated in Figs. 1 and 2.

The paper to be perforated is interposed 55 between the feed-rollers and pushed in against the gage-strip L intermediate of the perforated plates F G, to come under any of the dies that may be brought to the perforating-point. The action of the lever U effects the 60 perforating operation, and at the same time the pawl Y is swung around on the ratchet-wheel Z a predetermined number of notches by the exertion of said lever against the projection s on the loose counterweighted arm W, the area of the lever-opening r engaged 65 by said projection being sufficient to permit the automatic lift of a die to clear its receiver

in the lower perforated plate, G, and paper before the return stroke of the aforesaid lever begins to exert power on the aforesaid projection to operate said arm and thereby work the spacing mechanism comprising the pawl and ratchet and the feed-rollers. In other words, the hammer is retracted by the pull of its controlling-spring R, and the expansion 75 of the previously-contracted spring J surrounding a die-stem under said hammer causes said stem to return to normal position, as herein shown, before the pawl Y exerts power on the ratchet-wheel with which it is engaged.

Inasmuch as the lower boundary of the lever-opening r is normally against the arm projection s, it follows that the hammer does not begin to exert power on a die-stem until 85 the lever U has moved down far enough to bring the upper boundary of said opening against said projection.

The machine as herein shown has a perforating-die corresponding to the symbol "\$," and this symbol may be utilized to precede and succeed a word or combination of words perforated by one or more of the other dies in said machine. Instead of the symbol "\$" a star or other arbitrarily-selected symbol or 95 character may be employed.

The present machine is organized to perforate words denoting varying amounts from one to nine hundred ninety-nine thousand nine hundred ninety-nine, there being dies 100 for the words "one," "two," "three," "four," "five," "six," "seven," "eight," "nine," "ten," "eleven," "twelve," "twenty," "forty," the syllables "thir," "fif," "teen," "eigh," and "ty," and also the words "hundred" and 105 "thousand," as indicated in Fig. 4, representing a plan view of the index-plate that is rotatable with the die-carrying shell.

The dies and their receivers in the plate G are arranged to perforate on a straight line, 110 while the spacing mechanism or paper-feed is made variable to correspond with the reading length of said dies, provision being also made for spacing between words or between the arbitrary symbol and a word.

The length of each die-stem is proportioned 115 to the reading length of the symbol, syllable, or word to be perforated, and the greater this reading length the shorter said stem, in order that the pawl may be swung far enough around on the ratchet-wheel by the downstroke of the lever to obtain the proper spacing when said lever is on the upstroke.

When any one, except two, of the peripheral notches of the index-plate is engaged 120 with the spring-stop, the left of the reading matter of the corresponding die and its receiver is at the right of the imaginary line 125 delineated in Fig. 5, for the reason that the machine is schemed to have the left of said reading matter on all but two of the dies and their receivers four character-spaces from 130 a radial line passing through the center of the corresponding index-knob and peripheral

notch in said index-plate, as clearly expressed in full and dotted lines, Fig. 4.

The two exceptions to the above rule are the dies and their receivers for the suffix-syllables "teen" and "ty," the left of the reading matter pertaining to these dies and receivers being set five character-spaces from radial lines passing through their index-knobs and notches.

10 The stems of the dies for the arbitrary symbol and all the words and syllables above noted are of such respective length as to insure of the pawl being carried around on the ratchet-wheel as many notches as there are 15 characters belonging to any one of the dies plus one notch for the space to follow said symbol, word, or syllable when perforated in the paper fed to the machine, and thus when the spacing mechanism is operated said paper is carried along to the left between the feed-rollers a distance equal to the reading 20 length of a previously-actuated die and a succeeding space the same in width as a single die-character.

25 As to the suffix-syllables "teen" and "ty" the set of the same is such that the first letter of each strikes the paper to the left of the imaginary line 55 above noted, so as to come in the space succeeding a prefix syllable 30 or word and avoid a break in the completed word.

In matter of structural detail the machine above described may be somewhat varied without departure from the essential result 35 sought to be accomplished.

Having thus described my invention, what I claim as new, and desire to secure by Letters Patent, is—

1. A perforating-machine embodying reciprocal dies of different reading lengths, 40 receivers for the dies, a tilt-hammer for impacting said dies, a lever linked to the hammer, and a variable spacing mechanism comprising a pair of feed-rollers, a ratchet-wheel fast on the axle of one of the rollers, an actuating-pawl for the ratchet-wheel, and a pawl projection engaging an opening of suitable area in the lever.

2. A perforating-machine embodying reciprocal dies of different reading lengths, 50 receivers for the dies, a tilt-hammer for impacting the dies, a lever linked to the hammer, and a variable spacing mechanism comprising a pair of feed-rollers, a ratchet-wheel fast on the axle of one of the rollers, a counterweighted pawl operating in conjunction with the lever to actuate the ratchet-wheel and a pawl projection engaging an opening of suitable area in the lever.

60 3. A perforating-machine embodying a rotative shell provided with an inwardly-extended paper-support, reciprocal dies carried by the shell and having different reading lengths matching the perforations in said support, a tilt-hammer for impacting the dies, a variable spacing mechanism comprising a lever in link connection with the hammer, a

feed-roller having a ratchet-wheel on its axle, and a pawl operating in conjunction with the lever to actuate the ratchet-wheel; a housing 70 inclosing the shell, a spring-controlled frame in hinge connection with the housing and another feed-roller journaled in the frame parallel to the one aforesaid.

4. A perforating-machine embodying a rotative shell provided with an inwardly-extended perforated paper-support, reciprocal dies carried by the shell and having different reading lengths matching the perforations in said support, a tilt-hammer for the dies, a lever linked to the hammer, and a variable spacing mechanism in connection with the lever.

5. A perforating-machine embodying a rotative shell provided with an inwardly-extended perforated paper-support, reciprocal dies carried by the shell and having different reading lengths matching the perforations in said support, an index-plate rotative with the shell, a tilt-hammer for the dies, a lever linked to the hammer, and a variable spacing mechanism in connection with the lever.

6. A perforating-machine embodying a rotative shell provided with an inwardly-extended perforated paper-support, reciprocal dies carried by the shell and having different reading lengths matching the perforations in said support, an index-plate rotative with the shell, a stop for the plate, a tilt-hammer for the dies, a lever linked to the hammer, and a variable spacing mechanism co-operative with the lever.

7. A perforating-machine embodying a rotative shell provided with an inwardly-extended perforated paper-support, dies having stems of variable length reciprocal in the shell and their reading lengths proportioned to these stems as well as matched to the perforations in said support, a tilt-hammer arranged to operate against the die-stems, a lever linked to the hammer, and a variable spacing mechanism co-operative with the lever.

8. A perforating-machine embodying a housing having an interior track, a rotative shell having an outer flange that rests on said track and an inner paper-support provided with perforations, reciprocal dies in the shell having different reading lengths matching the perforations in said support, a tilt-hammer for the dies, a lever linked to the hammer, and a variable spacing mechanism co-operative with the lever.

9. A perforating-machine embodying a rotative shell having an inwardly-extended paper-support comprising a pair of parallel plates spaced apart, reciprocal dies in the shell having different reading lengths matching the perforations in the plates; a tilt-hammer for the dies, a lever in link connection with the hammer, and a variable spacing mechanism under control of the lever.

10. A perforating-machine for designating

on bank-checks or analogous orders in words any amount from one to nine hundred ninety-nine thousand nine hundred ninety-nine inclusive, the same comprising a rotative shell 5 a series of reciprocative dies carried by the shell and embraced in a scheme that essentially consists of the words "one," "two," "three," "four," "five," "six," "seven," "eight," "nine," "ten," "eleven," "twelve," "twenty," "forty," "hundred," "thousand," and the syllables "thir," "fif," "teen," "eigh," "ty," together with an arbitrary symbol other than a letter or word that may be utilized to precede or succeed a word or combination of the same; suitable means for impacting the dies at a common point, other suitable means for regulating the travel of each die in proportion to its reading length, a paper-support, extending in from the shell and having perforations that match the dies, 10 and the suitable means for regulating the travel of each die in proportion to its reading length, a paper-support, extending in from the shell and having perforations that match the dies, and a variable spacing mechanism co-operative with said dies.

15 20 11. A perforating-machine for designating on bank-checks or analogous orders in words any amount from one to nine hundred ninety-nine thousand nine hundred ninety-nine inclusive, the same comprising a rotative shell 25 a series of reciprocative dies carried by the

shell and embraced in a scheme that essentially consists of the words "one," "two," "three," "four," "five," "six," "seven," "eight," "nine," "ten," "eleven," "twelve," "twenty," "forty," "hundred," "thousand," and the syllables "thir," "fif," "teen," "eigh," "ty," together with an arbitrary symbol other than a letter or word that may be utilized to precede or succeed a word or combination of the same; suitable means for impacting the dies at a common point, other suitable means for regulating the travel of each die in proportion to its reading length, a paper-support, extending in from the shell and having perforations that match the dies, and a variable spacing mechanism co-operative with said dies.

In testimony that I claim the foregoing I have hereunto set my hand, at Milwaukee, in the county of Milwaukee and State of Wisconsin, in the presence of two witnesses.

ELLSWORTH GRIFFIN.
